UNITED STATES PATENT OFFICE.

SAMUEL BRAND, OF DAYTON, OHIO, ASSIGNEE, BY MESNE ASSIGNMENTS, TO THE NATIONAL CASH REGISTER COMPANY, OF DAYTON, OHIO, A CORPORATION OF MARYLAND.

CASH REGISTER.

Application filed April 9, 1923. Serial No. 630,955.

This invention relates to cash registers, and more particularly to the keyboards thereof, and their cooperating mechanisms.

The principal object of the present invention is to provide a machine of the general type shown herein with a novel keyboard and novel means for controlling the differential mechanism.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a sectional view through the machine taken just to the right of one of the differential units and shows the keyboard mechanism.

Fig. 2 is a detail side elevation of the double cam and pitman for operating the latch breaking mechanism.

Fig. 3 is a top plan view of the keyboard with the differential units, which cooperate therewith, shown diagrammatically.

Fig. 4 is a sectional plan view taken on the line 4—4 of Fig. 1, looking in the direction of the arrows.

Fig. 5 is a detail view of the mechanism for releasing the keys at the end of an operation of the machine.

Fig. 6 is a detail side elevation of the releasing mechanism of the machine.

Fig. 7 is a detail sectional view through a portion of the releasing mechanism shown in Fig. 6.

Fig. 8 is a side elevation showing the means for operating the machine by a crank as well as by a motor bar controlled electric motor.

Fig. 9 is a detail side elevation of one of the keys used in this machine, with part of its cooperating mechanism.

General description.

The machine to which this invention is applied is of the general type shown and described in U. S. Letters Patent of F. L. Fulley Nos. 1,242,170 and 1,394,256, issued Oct. 9, 1917, and Oct. 18, 1921, respectively, and an application of B. M. Shipley, No.

451,508, filed March 11, 1921. As shown in the drawings, there are provided four banks of amount keys, each bank consisting of a plurality of keys of different denomination, giving the machine a registering capacity of \$99.99. The keys used in this device are of the press-down type and are so constructed that if the wrong key has been depressed through error the depression of another key in the same bank will automatically release the first mentioned key. A novel mechanism is also provided which operates under the control of the depressed keys to break the latch of the differential mechanism in a position corresponding to the value of the key depressed.

Keyboard.

The machine includes main side frames 18 and 19 (Figs. 1 and 8) which support the main shafts of the machine. As shown in Figures 1 and 9, each of the keys 20 is pivotally mounted on a shaft 21 which is supported by side frames 22 and 23 suitably secured to the base of the machine (not shown). These keys are adapted to be depressed, that is, rocked counter-clockwise about the shaft 21, but this movement is limited by means of a rod 24 which extends through slots 25 cut in all of the keys (Figs. 1 and 3). The operation of the keys is what is known in the art as "flexible", that is, the depression of any key in a bank will automatically release any key in the same bank which has previously been depressed. The means for accomplishing this will now be described. Each of the key plates has a notch 26 cut therein. A plate 27 carried by a pair of arms 28 loosely mounted on a shaft 29 normally lies adjacent the notches 26. There is one of these plates 27 for each bank of keys, as can be seen from Fig. 4. The arms 28 tend to rock constantly in a clockwise direction due to the influence of a spring 30 which is stretched between a pin 31 carried by an extension of one of the arms 28 and any suitable point on the base of the machine. The keys 20 are normally held in their upper position by means of a spring 32 stretched between a pin carried by each key and a rod 33 running across the entire machine and supported by the side frames 22 and 23. It can be seen from the above that when any key is depressed an

inclined portion 34 thereof will contact with a beveled portion on the upper edge of the plate 27 and as the key is depressed will rock said plate downwardly until the notch 26 comes into alignment with said plate, whereupon the spring 30 will cause said plate 27 to move into said notch and thereby maintain the depressed key in its depressed position. If, however, any other key in the same bank is depressed, the cam portion 34 thereon will rock the plate 27 downwardly far enough to release the previously depressed key and at the same time engage the notch 26 and hold the key last depressed in its depressed position.

Mechanism is also provided for locking the depressed keys in their depressed positions, as well as locking the undepressed keys in their undepressed positions during the operation of the machine. This function is performed by a yoke 35 carried by a pair of arms 36 fast on a shaft 37 which is supported by the side frames 22 and 23. The shaft 37 is given a counter-clockwise rotation (Fig. 1) at the beginning of an operation of the machine in a manner which will herein-after be described. This movement of the shaft 37 will, through the arms 36, move the yoke 35 into engagement with the notches 26 in the undepressed keys and will at the same time take up a position just back of a shoulder 38 on any of the keys which have been depressed. This position of the yoke will be maintained until near the end of the operation of the machine and it will therefore positively lock the keys in either their depressed or undepressed positions.

Driving mechanism.

This machine is adapted to be driven either by means of a motor of any suitable design or by a crank handle 39 mounted on the right hand side of the machine (Fig. 8). If the crank handle is used to operate the machine, a pinion 40 carried thereby will be meshed with the teeth of a large gear 41 rotatably mounted on a stud 42 secured to the side frame 19 of the machine. This gear, in turn, meshes with a gear 43 fast on a shaft 44, which is the main drive shaft of the machine. The gearing just above described is so proportioned that two complete rotations of the crank handle 39 will cause the shaft 44 to receive one complete clockwise revolution, as viewed in Fig. 8. If a motor is used to drive the machine, it is connected to the shaft 44 by mechanism which is well known in the art and which is shown in the above mentioned patents and application. It is not thought necessary therefore to include any further description thereof herein.

Releasing mechanism.

As is usual in machines of this type, the

mechanism is normally locked, and manual means are provided for releasing said mechanism for operation. Reference may be made to the copending application of B. M. Shipley, Serial No. 635,927, for a detailed showing of this mechanism. If the machine is motor-driven the releasing mechanism also closes the motor circuit so that the operation will be commenced immediately. If, however, the machine is operated by the crank, the releasing mechanism must first be operated and then the crank handle be given two complete rotations. In order to effect this releasing movement of the machine there is provided a motor bar 45 (Fig. 8) which is supported by a plate 46 having a bifurcated end which straddles two lugs projecting from another plate 48 which, in turn, is supported by two studs 49 extending through slots 50 into the side frame 19 of the machine. The plate 48 also carries a stud 51 which projects into the bifurcated end 52 of a lever 53 mounted on a stud 54 projecting from the machine side frame. This lever 53 at its opposite end carries a pin 55 which extends into the bifurcated end 56 of an arm 57 loosely mounted on a shaft 58 supported by the machine side frames. The arm 57 is connected by a yoke 59 to a hook-shaped member 60 which is adapted to co-operate with a roller 61 carried by an arm 62 loose on a shaft 63, also supported by the machine side frames. The arm 62 is connected to another arm 64 by a yoke 65 (Fig. 7). The arm 64 at its lower end is formed with three teeth 66 which mesh with teeth 67 carried by a member 68 loosely mounted on the shaft 58 and which has a squared end against which normally rests a flat-sided stud carried by an arm 70 which is loose on the shaft 63. The arm 70 has a portion 71 which lies over a roller 72 carried by an arm 73 fast on the shaft 63. It can be seen from the above that when the bar is depressed to release the machine the plate 48 will be slid inwardly on the studs 49, and the stud 51, which engages with the bifurcated portion of the lever 53, will rock said lever counter-clockwise about the stud 54. This movement will cause the pin 55 carried by the opposite end of said lever, through its engagement with the bifurcated portion 56 of arm 57, to rock this arm, and through the yoke 59 the hooked portion 60 clockwise. This movement of the hooked portion 60 by means of its engagement with the roller 61 carried by the arm 62 will rock this arm, and through the yoke 65, the arm 64 clockwise. The arm 64, through the engagement of its teeth 66 with the teeth 67 on the member 68 will rotate this member counter-clockwise about the shaft 58 far enough to cause the squared end of the member 68 to pass out of engagement with the flat side of the stud 69 carried by the arm 130

70. The shaft 63 constantly tends to rock in a clockwise direction under the influence of a powerful spring 75 (Fig. 8). Therefore, when the arm 70 is permitted to rock in a clockwise direction, as above described, the spring 75 will cause the shaft 63 and arm 73 to rock clockwise and thereby bring the flat-sided stud 69 into a position between the member 68 and a member 76 which is loose on the shaft 58 but which is held in engagement with the member 68 by means of a spring 77.

The spring 75, which constantly tends to rock the shaft 63 in a clockwise direction, is compressed between the bottom of a slot 78 in a link 79 (Fig. 8) and a shoulder formed on two members 80 which are pivoted to an arm 81 fast on the shaft 63. The stud which forms the pivot of the members 80 is carried by the arm 81 and projects through a slot 82 in the upper end of the link 79. The clockwise movement of the arm 81 and shaft 63 is limited by a stud 83 projecting from the side frame of the machine into the path of movement of a projection 84 integral with the arm 81.

It will be recalled that the yoke 35 is moved into engagement with the notches 26 in the keys to lock the keys against depression and into engagement with the shoulder 38 of said keys to prevent the release of the depressed keys during the operation of the machine. The means for rocking the yoke 35 to accomplish this function will now be described. Fast on the shaft 37 which carries the yoke 35 is an arm 85 (Fig. 5) to which is pivoted a link 86, which at its other end is pivoted to an arm 87 loose on a shaft 88 which is supported by the side frames 22 and 23. The arm 87 is connected by a hub 91 (Fig. 3) to a similar arm 89, to which is pivoted a link 90. This link at its upper end is pivoted to an arm 101 which is fast on the shaft 63. It can be seen from Fig. 5 that when the shaft 63 is given its clockwise rocking movement the link 90 will be raised, and through the arm 89, hub 91 and arm 87 the link 86 will be moved toward the right, as seen in this figure, and therefore the arm 85 and shaft 37 will be rocked counter-clockwise a sufficient distance to raise the yoke 35 into engagement with the notches 26 in the keys, as above described.

55 *Differential mechanism.*

The differential mechanism shown in connection with this invention is identical with that shown and described in the above mentioned patents and application, and therefore only a very brief description thereof will be included herein. The differential mechanism is driven by means of a pair of cams 102 and 103 which cooperate with anti-friction rollers 104 and 105 respectively carried by a Y-shaped member 106, pivoted to a frame

107 at 1070, which partially supports each differential unit. The frame 107 is supported by rods 108 and 109 mounted in the side frames of the machine. At its upper end the Y-shaped member 106 is pivoted to a link 110 which at its other end is pivoted to a driving segment 111 rotatably mounted on a bushing 112 supported by the frames 107. Also mounted on the bushing 112 is a pair of differentially movable plates 113 between 75 which are mounted actuating segments 114. The cams 102 and 103 are fast on the main drive shaft 44 and are given a complete clockwise rotation on every operation of the machine. This movement, through the Y-shaped member 106 and link 110, causes the driving segment 111 to be given first a clockwise and then a counter-clockwise movement. The plates 113 are connected to the driving segment 111 by means of a latch 99 pivotally mounted on an arm 115 and a bell crank 116 carried by the plates 113. The inner end of the latch 99 engages a shoulder 117 formed on the periphery of the driving segment 111. The latch is normally maintained in its inner position by means of a spring 118 stretched between the upper end of the bell crank 116 and a pin on the hub of the plates 113. The cams 102 and 103 for the various groups of keys are timed to move the actuating segments 111 upwardly simultaneously and to return them to effect transfers successively. 95

The plates 113 are rotated by the driving segment 111 in a clockwise direction, and in order to properly add, indicate and print the amounts set up on the keyboard the latch 99 of the differential mechanism must be broken when the plates 113 reach a position corresponding to the value of the key depressed in their appropriate banks. In 105 order to accomplish this result the following mechanism has been designed.

Each of the keys 20 has a downwardly extending tail 120 which has formed thereon a shoulder 121. These shoulders are located at 110 different distances from the upper ends 122 of said tails, depending on the value of its corresponding key (see Figs. 1 and 9). Adjacent each of the banks of keys is an arm 123 pivoted on a shaft 88 having a curved slot 115 124 formed therein. Projecting into this slot is one end of a rod 125 (Fig. 4) which is supported by a pair of arms 126 fast thereto. The arms 126 are pinned to a shaft 127 which is loosely mounted in the ends of two arms 128 fast on a shaft 129 supported by the machine side frames. Also fast on the shaft 129 is a downwardly extending arm 131 to which is pivoted one end of a pitman 132 (Figs. 1 and 2). The pitman 132 is slotted at its rear end to receive the main drive shaft 44 and carries two anti-friction rollers 133 and 134 which cooperate with a pair of cams 135 and 136 respectively, fast on the shaft 44. 125 The shaft 44 is given a complete clockwise 130

rotation on each operation of the machine, and through the cams 135 and 136 moves the pitman rearwardly, which movement by means of the arm 131 rocks the shaft 129 counter-clockwise (Fig. 2). As the pairs of arms 128, (each of said pairs being appropriate to one of the banks of keys) are fast on the shaft 129, they will be rocked counter-clockwise (Fig. 1) and will lower the shafts 127, and through the arms 126 fast thereto will lower their rods 125 in the slots 124 and then return said rods to their normal positions.

It can be seen from Fig. 1 that the depression of any of the keys in a bank will move its corresponding shoulder into such a position as to obstruct the passage of the rod 125 at a certain point in its travel in the slot 124. Therefore, when the rod 125 comes in contact with the shoulder 121 it will cause the rod 125 and arms 126 to be rocked clockwise about the shaft 127, and as the end of the rod 125 travels in the slot 124 the arm 123 will be rocked counter-clockwise with said rod. It can be seen that the rocking movement of the rod 125 will take place at different times during the downward movement of the rod, depending upon which one of the keys in its corresponding bank of keys has been depressed.

The arm 123 for the tens of dollars bank (Fig. 3) is fast to the shaft 88. Also fast to this shaft is an arm 138 which extends upwardly and at its upper end is bifurcated to cooperate with a pin 139 carried by a lever 140 which is pivoted to a segmental plate 141 supported at its lower end on the rod 109 and at its upper end on a rod 142.

A lever 143 similar to the lever 140 is pivoted on the plate 141 and has a bifurcated portion 144 cooperating with the pin 139. At its upper end the lever 143 is pivoted to a plate 145, which plate at its lower end carries a roller 146 adapted to cooperate with a bifurcated portion 147 in the lower end of the lever 140. The levers 140 and 143 are held in their normal positions, as seen in Fig. 1, by means of a spring 148 stretched between pins carried by extensions 149 of said levers.

It can be seen from the above description that when the lever 123 is rocked counter-clockwise, due to the engagement of the rod 125 with the shoulder 121 on the tail 120 of the depressed key and the subsequent camming action thereof, the arm 123 will impart a counterclockwise movement to shaft 88 and arm 138. This movement, through the cooperation of the bifurcated portion in the upper end of the arm 138 with the pin 139 will rock the lever 140 counter-clockwise and the lever 143 clockwise simultaneously. As the opposite ends of the levers 140 and 143 are connected to the plate 145 it can be seen that this plate will move

inwardly radially toward the center of the differential mechanism (Fig. 1). The parts are so timed that as the differentially movable members 113 carrying the actuating segments 114 are given their clockwise rotation the plate 145 will be moved inwardly just in time for the appropriate one of a series of notches 150 formed on the inner edge of said plate to engage the forward end of the bell crank 116 and thereby break the latch of the differential mechanism in the position appropriate to the value of the key depressed. When the latch is broken the forward end of the latch member 99 will come into engagement with one of a series of notches 151 formed in the inner edge of the plate 141 above described. The mechanism above described is for the tens of dollars bank of keys. The means for connecting the arms 123 of the units of dollars, tens of cents and units of cents banks with their appropriate arms 138 can be seen in Fig. 3, and consist of sleeves 152 which surround the shaft 88 and are supported thereby.

When the driving segment 111 upon its counter-clockwise return movement reaches the position at which the latch was broken, the spring 118 will move the latch member 99 rearwardly and once more engage said latch with the shoulder 117 of the driving segment and the differentially movable plates 113 will then be returned to home position by the engagement of a pin 153 carried thereby with the upper end of the driving segment 111.

It will be noted from Fig. 1 that the radially movable plate 145 has only seven notches cut therein. When the latch is to be broken in the first position the bell crank 116 comes in contact with the lower edge of the plate 145 and thereby breaks the latch. When the latch is to be broken in the ninth position the plate 145 is only partially moved, as there is no shoulder appropriate to the ninth position on the plate 145. When this condition arises the latch will be broken by the engagement of the bell crank 116 with a lug 154 carried by the plate 141. In case no key in a bank is depressed, a zero stop pawl 156 is provided, which will break the differential latch in the zero position. This zero stop pawl is normally in position to engage the end of an arm 157 projecting from a plate (not shown herein) but which can be seen in the beforementioned patents and application. The end of this plate 157 is bifurcated and cooperates with a pin 158 projecting laterally from the end of the bell crank 116. It can therefore be seen that as the differential mechanism moves in its clockwise direction, the end of the arm 157 will come in contact with the zero stop pawl 156, and, due to the engagement of the pin 158 with said arm, will rock the bell crank 116 and thereby break the latch, as above de-

scribed. The zero stop pawl is maintained in its normal position, as shown in Fig. 1, by means of a spring 159 stretched between a pin on the plate 141 and a pin carried by an extension of said pawl. If any key in a bank is depressed, the upper end 122 of its tail 120 will give the rod 125 a slight clockwise movement, which movement will be transmitted to the arm 123, shaft 88 and arm 138, as above described. Each of the arms 138 has a downwardly extending curved portion 160 which normally contacts with a pin 161 carried by a downwardly extending portion 162 of its appropriate zero stop pawl. It is therefore evident that as the arm 138 is given a slight counter-clockwise rotation upon the depression of any of the keys in its bank, the lower end 160 thereof will also move in a counter-clockwise direction, and through its engagement with the pin 161 will rock the zero stop pawl counter-clockwise out of its effective position.

It is desired on totalizing operations to have all the zero stop pawls rocked out of effective position, and this is accomplished by means of a rod 163 carried by arms 164 fast on a shaft 165 supported by the machine side frames. This shaft 165 is rocked in a clockwise direction by mechanism controlled by a movement of the total lever, used in machines of this class, to any of its totalizing positions. This mechanism, through the engagement of the rod 163 with a surface 191 on each pawl, will rock all of the zero stop pawls 156 counterclockwise to ineffective position.

Totalizers.

The totalizers used in this machine comprise a plurality of groups of totalizer pins 166 loosely mounted on tubes 167. Mechanism is provided for shifting these groups of totalizers laterally of the machine to select any desired group thereon, and other mechanism is provided for rocking this group into engagement with the differential actuating segments 114 in order that its elements may be rotated to the extent determined by the depressed keys. Neither the mechanism for shifting the totalizer lines nor that for engaging them with the actuating segments is shown herein, as they have nothing whatever to do with the present invention and are fully shown and described in the beforementioned patents and application.

Indicators.

Each of the differential units has a beam 168 (Fig. 1) pivoted to one of the plates 113 and at its rear end bifurcated to cooperate with a pin carried about midway of a link 169. As is well known in the art link 169 is given the differential adjustment of the actuating segments due to the engagement of a roller 98 carried by member 106 with the

beam 168. Pivoted to the upper end of the link 169 is an indicator actuating segment 170. This segment carries teeth 171 which are adapted to cooperate with and select the indicators for this bank of keys. As these indicators form no part of the present invention they have been omitted from both the showing and the description herein. The segment 170 also has teeth 172 formed thereon with which an alining plate 173 is adapted to cooperate. This alining plate is carried by a plurality of arms 174 fast on a shaft 175. At the beginning of an operation the shaft 175, arms 174 and plate 173 are given a clockwise rotation to disengage the plate 173 from the teeth 172. The differential mechanism is then operated, and when it has received its differential movement the alining plate 173 is once more engaged with the teeth 172 and thereby properly alines the parts of the differential mechanism.

Printer.

At its lower end the link 169 appropriate to each differential unit is pivoted to an arm 176 which is fast on a shaft 177 or one of a plurality of sleeves 178 surrounding said shaft. This shaft and the sleeves supported thereby carry at their opposite ends appropriate type wheels which cooperate with other mechanism to print the amount registered by the differential mechanism on the totalizers. This mechanism, however, need not be considered in the description of the present invention and no further mention thereof will be made herein.

Means for releasing keys at the end of an operation.

It will be remembered that the shaft 63 is given a clockwise movement in order to release the machine for operation by the spring 75 (Fig. 8). It is therefore necessary at the end of an operation to return this shaft to its normal position and this object is accomplished in the following manner. Pivoted on a stud 180 is a curved arm 181 which carries a pin 182 in engagement with a recess 183 formed in an opening 184 in the link 79. The arm 181 carries a roller 185 which is adapted to cooperate with a cam groove 186 formed in the large gear 41, previously described. It will be remembered that this gear is given one-half of a complete rotation at each operation of the machine. The cam groove 186 is therefore provided with two cam portions 187 which will cooperate with the roller 185 at the extreme end of the operation of the machine and thereby rock said arm first clockwise and then counter-clockwise to its normal position. Upon the clockwise movement of the arm 181 the pin 182 will move the link 179 downwardly, which movement will rock the arm 81 and shaft 62.

counter-clockwise a little past normal position. When this occurs the pin 72 which is carried by the arm 73 fast on the shaft 63 comes in contact with a surface 188 of a restoring member 189 which is loosely mounted on the shaft 58 (Fig. 6) and thereby rocks said restoring member counter-clockwise. This restoring member 189 has a tail 190 which cooperates with an extension of the pin 69 so that when the member 189 is given its counter-clockwise movement, as above described, the tail 190 will rock the arm 70 carrying the pin counter-clockwise about the shaft 63 far enough to permit the spring 77 to return the member 68 to its normal position behind the pin 69. The shaft 63 is then rocked slightly clockwise to normal and held in its normal position, as shown in Fig. 7. The return movement of the shaft 63 to normal position, through the link 90, arm 89, sleeve 91, arm 87 and link 86 rocks the arm 85 in a clockwise direction (Fig. 5). The arm 85 has a downwardly extending portion 200 carrying a pin 201 adapted to cooperate with the end of a lever 202 which is fast on the extreme left hand end of the shaft 29. Also fast on the shaft 29 are two arms 203 which carry pins 204. These pins normally lie adjacent to upwardly extending projections 205 carried by one arm of each of the pairs of arms 28 which support the latching plates 27 for the keys (Fig. 4). When the arm 85 is given its clockwise movement, as just described, the pin 201 will engage the end of the arm 202 and rock this arm counter-clockwise (Fig. 5). As this arm is fast to the shaft 29 this shaft will also be given a counter-clockwise movement, as seen in Fig. 1, which will cause the arms 203 to come in contact with the upwardly extending portions 205 of the arms 28 and rock these arms and the plate 27 carried thereby downwardly out of engagement with the notch 26 of the key depressed in this bank. The rocking of the arm 85 in a clockwise direction, as just above described, will rock the shaft 37 in the same direction, which movement will cause the arms 36 carrying the yoke member 35 to be rocked clockwise to remove the yoke member from its engagement with the notches 26 of the undepressed keys and the shoulder 38 of the depressed keys. As both the latching plate 27 and the yoke member 35 are now removed, the springs 32 will return the depressed keys to their normal undepressed positions.

Totalizing.

No means is shown or described in this application for taking totals or sub-totals. The mechanism shown and described in the beforementioned patents and application is capable of use with this machine and it is not thought necessary therefore to include

this portion of the machine in the drawings 65 or specification.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow. 70

What is claimed is:

1. In a cash register, the combination of a differentially movable member, driving means therefor, means for latching said movable member to said driving means, and a notched plate adapted to be interposed 85 into the path of said latching means during the operation of the machine in order to break said latch.

2. In a cash register, the combination of differential mechanism, driving means 33 therefor, means for latching said differential mechanism to said driving means, a notched plate adapted to be moved into the path of said latch during operations of the machine, means for carrying said plate, and means cooperating with said last mentioned means for moving said plate. 90

3. In a cash register, the combination of differential mechanism, driving means therefor, means for latching said differential mechanism to said driving means, a notched plate adapted to be moved radially into the path of movement of said latch during the operation of said machine, a plurality of 95 arms for carrying said plate, and means for moving said arms. 100

4. In a cash register, the combination of differential mechanism, driving means therefor, means for latching said differential mechanism to said driving means, a notched plate adapted to be moved radially into the path of movement of said latch during the operation of said machine, a plurality of 105 arms for carrying said plate, and a pivotally mounted arm connected to all of said first mentioned arms for moving said plate. 110

5. In a cash register, the combination of differential mechanism, driving means therefor, means for latching said differential mechanism to said driving means, a notched plate adapted to be moved radially into the path of movement of said latch during the operation of said machine, a plurality of 115 arms for carrying said plate, a pivotally mounted arm connected to said first mentioned arms, and means operated by said driving means for operating said notched plate. 120

6. In a cash register, the combination of 125 a differentially movable member, driving means therefor, means for latching said movable member to said driving means, a segmental stop plate adapted to be inter-

posed into the path of said latching means during the operation of the machine in order to break said latch, and a plurality of manipulative devices for controlling the

5 movement of said segmental stop plate.

7. In a cash register, the combination of differential mechanism, driving means therefor, means for latching said differential mechanism to said driving means, a segmental stop plate adapted to be moved into the path of said latch during operations of the machine, means for carrying said plate, means for moving said plate, and a plurality of keys for controlling said movement.

8. In a cash register, the combination of differential mechanism, driving means therefor, means for latching said differential mechanism to said driving means, a segmental stop plate adapted to be moved radially into the path of movement of said latch during the operation of said machine, a plurality of arms for carrying said plate, means for moving said arms, and a plurality of keys for controlling the movement of said last mentioned means.

9. In a cash register, the combination of differential mechanism, driving means therefor, means for latching said differential mechanism to said driving means, a segmental stop plate adapted to be moved radially into the path of movement of said latch during the operation of said machine, a plurality of arms for carrying said plate, a pivotally mounted arm connected to all of said first-mentioned arms for moving said plate, and a plurality of keys for controlling the movement of said pivotally mounted arm.

40 10. In a cash register, the combination of differential mechanism, driving means therefor, means for latching said differential mechanism to said driving means, a stop plate adapted to be moved into the path of movement of said latch during the operation of said machine, a plurality of arms for carrying said stop plate, a pivotally mounted arm connected to said first-mentioned arms, means operated by said driving means for operating said stop plate, and a plurality of keys for controlling said operated means.

11. In a cash register, the combination of differential mechanism, driving means therefor, means for latching said differential mechanism to said driving means, a stop plate adapted to be moved radially into the path of movement of said latch during the operation of the machine, a plurality of arms for carrying said plate, a pivotally mounted arm connected to said first-mentioned arms, means for giving said second-mentioned arm a rocking movement to move said stop plate into the path of movement

of said latch, and a plurality of manipulative devices for determining the point during 65 the operation of the machine when said stop plate will be moved.

12. In a machine of the class described, the combination of differential mechanism, driving means therefor, latching means for said differential mechanism and said driving means, means for breaking said latch in any one of a plurality of positions, operating means therefor, a separate means for breaking said latch in its lowermost position, 75 and means integral with said operating means for disabling said separate means.

13. In a cash register, the combination of a plurality of pivotally mounted keys, plates integral with said keys, differential 80 mechanism cooperating with said keys, and differentially positioned means carried by said plates for controlling the extent of movement of said differential mechanism.

14. In a cash register, the combination 85 of a plurality of pivotally mounted keys, downwardly extending portions integral with said keys, differential mechanism cooperating with said keys, and a plurality of differentially located shoulders on said 90 downwardly extending portions for controlling the extent of movement of said differential mechanism.

15. In a cash register, the combination of a plurality of pivoted keys, differential 95 mechanism cooperating with said keys, downwardly extending portions integral with said keys, a plurality of differentially placed shoulders on said downwardly extending portions, a pivoted arm having a curved slot therein adjacent said keys, a rod adapted to slide in said slot, means whereby the depression of a key brings its appropriate shoulder into alinement with said slot, means for lowering said rod in said slot until it comes in contact with said shoulder whereupon the rod will be cammed backward and will rock said pivoted arm, a radially mounted notched plate adapted to stop said 105 differential mechanism at any desired point, and connections between said pivoted arm and said notched plate whereby the movement of said arm will operate said plate.

16. In a machine of the class described, the combination of a plurality of pivoted keys, plates integral with said keys, differential mechanism, latching means therefor, a plate adapted to break said latch, and differentially positioned means carried by said plates for determining at what point in the travel of said differential mechanism said plate shall break said latch.

In testimony whereof I affix my signature.

SAMUEL BRAND.
